Inventor

C. C. ELLIS.

By A. S. McFandie

Attorney

UNITED STATES PATENT OFFICE.

CHARLES C. ELLIS, OF CHATTANOOGA, TENNESSEE.

AMALGAMATING APPARATUS.

1,411,773.

Specification of Letters Patent. Patented Apr. 4, 1922.

Application filed July 12, 1920. Serial No. 395,541.

To all whom it may concern:

Be it known that CHARLES C. ELLIS, a citizen of the United States, residing at Chattanooga, in the county of Hamilton and State 5 of Tennessee, has invented certain new and useful Improvements in Amalgamating Apparatus, of which the following is a specification.

This invention relates to improvements in 10 amalgamators particularly designed for the amalgamation of gold and silver ores.

The primary object of the invention is to provide an amalgamating table, which will more effectively amalgamate the ores than 15 apparatus heretofore used.

With the foregoing object outlined and with other objects in view, the invention consists in the novel features hereinafter described in detail, illustrated in the accompanying drawings, and more particularly pointed out in the appended claims.

Referring to the drawings:—

Fig. 1 is a perspective view of my improved apparatus.

Fig. 2 is a vertical sectional view of the same.

In the drawings, 1 designates a standard or column having a base 2 that is designed to be secured to any suitable support.

30 The upper end of the column is provided with a stud 3 which is pivotally secured by means of a bolt and nut 4, to the bifurcated end 5 of a table support 6. On this support is rotatably mounted an amalgamating table 7, and a ball race and bearings 8 is located between the periphery of the support and said table to ensure easy running. A pin 9 on the support enters an aperture in the table to prevent the table from sliding off the support when said support is tilted, as shown 40 in Fig. 2.

The support carries a plurality of bearings 10 in which is rotatably mounted a shaft 11 having a fixed bevel gear 12 that 45 meshes with a large bevel gear 13 secured to the underside of the table. The shaft has a fixed pulley 14 which may be driven from any suitable power unit, and when the shaft 11 is driven the table will be rotated.

50 Mounted on the top of the table is a circular plate 15 of silvered copper and this plate has a downwardly projecting stud 16 that enters the orifice 17 in the table and secures the plate in position.

55 Extending vertically on opposite sides of the standard 1 are brackets 18 having their

upper ends provided with bolts and nuts 19. Posts 20 are adjustably secured to the brackets by means of bolts and nuts 19 which pass through the slots 21 in said posts. Each 60 post carries a socket 22 through which extends a horizontal arm 23, that carries a brush 24. Screws 25 are employed to lock the arms 23 in adjusted positions.

A feed launder 26, shown only in Fig. 2, 65 is used to deposit the material to be amalgamated on the plate 15, and a discharge trough 27 is employed to receive the water and pulp which passes off of the table.

When the bolt and nut connection 4 is 70 loosened, the table and plate 15 may be tilted to any angle to regulate the flow of water, pulverized ore, sand or any other material to be amalgamated, and it will be understood that such substances will flow or move by 75 gravity toward the edge of the table that is lowest. As the material flows over the table or plate, said plate is slowly revolved and this tends to separate the gold or silver from the water and pulp and the valuable substances adhere to the silvered copper plate 80 while the water and pulp flow off into the discharge chute 27.

It will be noted that the material is fed onto the plate at a point midway between the 85 brushes 24 and the brushes function to wipe slimes from the plate. These brushes may be made of any suitable fibre, bristles or the like and they may be adjusted both vertically and horizontally to accommodate adjustments of the table.

From the foregoing I believe that the practical operation and advantages of my apparatus may be clearly understood by those skilled in the art, and I am aware that 95 various modifications may be made in the construction disclosed without departing from the spirit of the invention as set forth in the following claims.

What I claim and desire to secure by Letters Patent is:—

1. An amalgamating apparatus including a flat circular plate of silvered copper adapted to support a coating of amalgam, means for rotating said plate about an axis 105 inclined to the vertical, means for feeding the material to be amalgamated onto the highest portion of said plate, and a plurality of soft brushes positioned above said plate and arranged to contact with the amalgam 110 carried by the plate and adapted to prevent slimes from settling on the amalgam.

2. A method of amalgamating consisting in feeding the material to be amalgamated onto a plane silvered copper amalgamating surface rotating in an inclined plane, discharging the water and pulp from the lowest edge of said table, and simultaneously brushing the slimes from the amalgamating surface and forming grooves in the amalgam to receive the precious metals.
- 5 3. An amalgamating apparatus comprising

ing a substantially flat silvered copper amalgamating plate rotatable about an axis inclined to the vertical, a plurality of parallel brushes resting on the table and arranged at opposite sides of the table axis, and means for feeding the material to be amalgamated onto the highest side of said plate between said brushes.

In testimony whereof I affix my signature.
CHARLES C. ELLIS.
